UNITED STATES PATENT OFFICE

AXEL V. JENSEN, OF COPENHAGEN, DENMARK, ASSIGNOR TO F. L. SMITH & CO., OF NEW YORK, N. Y., A CORPORATION OF NEW JERSEY

ROTARY CEMENT-BURNING KILN

Application filed April 25, 1928, Serial No. 272,631, and in Great Britain November 28, 1927.

In rotary cement burning kilns as employed in the wet process the slurry, in a semi-fluid condition, is commonly introduced into the feeding end of the kiln through a pipe or chute which is extended into the kiln through the dust chamber which encloses the end of the kiln. The products of combustion escape from the kiln through its end which is usually flanged inwardly in order to prevent the escape of slurry into the dust chamber. The area of the opening through which the products of combustion escape must be substantial and the depth of the flange is limited accordingly. In the operation of modern kilns of high capacity it sometimes happens that the escape of slurry into the dust chamber is not entirely prevented and it is the object of the present invention to overcome this difficulty. In accordance with the invention, therefore, the kiln is provided with an end wall which has a much smaller central opening than has been usual heretofore through which the slurry delivery pipe or chute may be extended within the kiln. The opening in the end plate, although it may permit the escape of some of the products of combustion, is not sufficiently large to permit the free escape thereof and accordingly outlets for the escape of the products of combustion within the zone of the dust chamber are formed in the circumferential wall of the kiln and guards are provided to prevent the escape of slurry through such outlets.

The invention will be more fully explained hereinafter with reference to the accompanying drawings in which it is illustrated and in which:

Figure 1 is a view in sectional elevation on the plane indicated by the broken line B—B of Figure 2, showing so much of a rotary kiln with the dust chamber and slurry tube as is necessary to enable the application of the invention thereto to be understood.

Figure 2 is a view in transverse section through the kiln on the plane indicated by the broken line A—A of Figure 1.

Figure 3 is a view similar to Figure 1 but showing a modified form of the invention,

the plane of section being indicated by the broken line C—C of Figure 4.

Figure 4 is a view in transverse section of the kiln, the plane of section being indicated by the broken line D—D of Figure 3.

Figure 5 is a detail view in section on the plane indicated by the broken line E—E of Figure 4.

In the embodiment of the invention shown in Figures 1 and 2 the upper or feeding end of the kiln *a* is shown as projected within the dust chamber *b* but not through the same. The dust chamber is connected as usual to the stack. The extreme end of the kiln is closed by an end plate *c* except for a relatively small central opening through which the slurry tube *d* is extended within the kiln for the delivery of slurry into the kiln. The central opening *c* in the end plate *c* may be of such size to permit the escape of some of the products of combustion but is not of such size as to make the escape of slurry possible. In the circumferential wall of the kiln, within the zone of the dust chamber, are formed outlets *e*, *e* through which the products of combustion find free escape into the dust chamber. Each of such outlets *e* is provided with a guard which prevents the escape of slurry through the outlet. Preferably, in the construction shown in Figures 1 and 2, the outlets *e*, *e* are arranged in diametric pairs and are connected by a tube *f* open at its ends and provided on the side toward the lower or discharge end of the kiln with an opening *f*, between its ends, through which the products of combustion may pass into the tube *f* and may escape therefrom through the outlets *e* into the dust chamber *b*. The tubes *f* of which there may be one or more, constitute a guard means to prevent the escape of slurry through the outlets *e* while permitting the free escape of the products of combustion.

In the embodiment of the invention illustrated in Figures 3, 4 and 5 the kiln *a* is shown as extended within the dust chamber *b* as before, and as having an end plate *c* with a relatively small central opening *c* through which the slurry chute *d* is directed within the kiln. The kiln is shown as pro-

100

vided in its circumferential wall with outlets e^1 which may be arranged opposite each other as shown, but offset somewhat. In this instance a guard device or tube f^2 is shown as provided for each outlet e^1 and as having an opening f^3 at the center of the kiln for the escape of the products of combustion. In the embodiment of the invention shown in Figures 1 and 2 each guard tube f is shown as rectangular in cross section, but in the embodiment of the invention shown in Figures 3, 4 and 5 it is shown as so twisted with reference to the direction of rotation of the kiln as to promote the movement of the slurry in the kiln toward the discharge end.

It will be understood that various changes in details of construction and arrangement may be made to suit different conditions of use and except as pointed out in the accompanying claims the invention is not limited to the construction shown and described herein.

I claim as my invention:

1. The combination of a rotary cement burning kiln, a dust chamber about the feed end of the kiln and a slurry chute, the kiln having an end plate with a central opening for the entrance of the slurry chute, and having in its circumferential wall in the zone of the dust chamber an opening for the escape of substantially all of the products of combustion, and a guard within the kiln to prevent the escape of slurry through such opening in the circumferential wall.
2. The combination of a rotary cement burning kiln, a dust chamber about the feed end of the kiln and a slurry chute, the kiln having an end plate with a central opening for the entrance of the slurry chute, and having in its circumferential wall in the zone of the dust chamber an opening for the escape of substantially all of the products of combustion, and a guard tube within the kiln communicating with such opening in the circumferential wall and having an opening in the center of the kiln for the escape of the products of combustion into the dust chamber.

This application signed this 10th day of April, A. D. 1928.

AXEL V. JENSEN.
